Primary Examiner — Michelle E. Wilson*Assistant Examiner* — Caitlin A Laverty(57) **CLAIM**

The ornamental design for a plastic quad cane base, as shown and described.

DESCRIPTION

FIG. 1 is a top front perspective view of a plastic quad cane base.

FIG. 2 is a front view of a plastic quad cane base.

FIG. 3 is a back view of a plastic quad cane base.

FIG. 4 is a right-side view of a plastic quad cane base.

FIG. 5 is a left-side view of a plastic quad cane base.

FIG. 6 is a top view of a plastic quad cane base.

FIG. 7 is a bottom view of a plastic quad cane base; and, FIG. 8 is a top front perspective view of a plastic quad cane base, without environmental structure shown in broken lines.

The broken lines are included for the purpose of showing environmental structure and form no part of the claimed design.
